UNITED STATES PATENT OFFICE

159,557

COCKTAIL GLASS OR THE LIKE

Joseph Strauss, Hewlett, N. Y., assignor to Weil
Ceramics & Glass, Inc., New York, N. Y.

Application July 1, 1949, Serial No. 3,663

Term of patent 3½ years

(Cl. D36—8)

To all whom it may concern:

Be it known that I, Joseph Strauss, a citizen of the United States of America and residing in Hewlett, county of Nassau, State of New York, have invented a new, original, and ornamental Design for a Cocktail Glass or the like, of which the following is a specification, reference being made to the accompanying drawing, forming part thereof.

Fig. 1 is an elevational view of a cocktail glass or the like showing my new design;

Fig. 2 is a top plan view; and

Fig. 3 is a bottom plan view thereof.

I claim:

The ornamental design for a cocktail glass or the like, substantially as shown.

JOSEPH STRAUSS.
